PREPARATION OF N¹-ACYL SULFANILAMIDE

William B. Tarpley, Jr., Chatham, N. J., and August I. Ryer, New York, N. Y., assignors to Schering Corporation, Bloomfield, N. J., a corporation of New Jersey

No Drawing. Application December 10, 1943,
Serial No. 513,716

8 Claims. (Cl. 260—397.7)

1

The present application relates to an improved process for the manufacture of N¹-acyl sulfanilamides, and to certain intermediate products obtained in the course of such process.

The N¹-acyl sulfanilamides cannot be prepared by the direct treatment of sulfanilamide with an acylating agent, at least not in commercially satisfactory yields. Treatment of sulfanilamides with an acylating agent at relatively low temperatures or with one of the less active acylating agents usually produces only the N⁴-acyl derivative, or, in a greatly preponderating proportion at higher temperatures, the N¹, N⁴-diacyl derivatives are produced.

The only commercial method for the manufacture of the N¹-acyl sulfanilamides, a number of which have been found to be important therapeutic agents, has been by a multi-step process (Crossley, Northey & Hultquist, J. A. C. S. 61, 2950-5, 1939; and K. A. Jensen and F. Lundquist, Dansk Tidsskrift for Farmaci 14, 129-33, 1940) but the yields have been rather low. The most widely used method has been to treat an N⁴-acyl sulfanilamide with an acylating agent, such as an acyl anhydride or an acyl chloride. The thus-formed N¹, N⁴-diacyl compound is then subjected to a partial hydrolysis whereby the N⁴-acyl group is split off, yielding the N¹-acyl sulfanilamide. This last step is mainly responsible for the low yield of the desired N¹-acyl compound, for the hydrolysis of the acyl compound yields also the completely deacylated product, namely sulfanilamide, while some of the diacyl compound remain unreacted. The further purification of the mixture involves additional expense and further reduction in the yield. Low yields are obtained even when the N⁴-acyl group is one which splits off more readily on hydrolysis than the N¹-group. Where the N¹-acyl group is one which is relatively easy to hydrolyze, further difficulties are encountered in the known procedure in the attempt to obtain a satisfactory yield.

It will be recognized that in the known procedure where different acyl groups are to be attached to the N¹ and N⁴, a two-step acylation process is required. In addition, it is important in the known procedures to attach to the N⁴-atom an acyl group which is in all cases more readily hydrolyzable than the N¹-acyl group, regardless

2

of how easily hydrolyzable the latter may be. Also, no matter how easily hydrolyzable the N⁴-acyl group may be, the hydrolysis step must usually be so vigorous that a considerable amount of hydrolysis takes place also at the N¹ group.

According to the present invention the N¹-mono-acylation of the sulfanilamide, and substantially exclusively at the N¹-position, is accomplished in a single step, and an intermediate mono-acylated product is obtained which is easily converted to the N¹-acyl sulfanilamide with practically no danger of hydrolysis at the N¹-group.

We have found that N¹-acyl sulfanilamides, 15 non-acylated at the N⁴-position, can be prepared in much higher yields than formerly and in a single acylation step, without the necessity for any vigorous subsequent hydrolysis, and by starting with the readily obtainable parent compound, 20 sulfanilamide. The present invention is based upon our discovery that the p-amino group can be bound by a strong acid and thereby rendered inactive toward the acylating agent employed for making the N¹-acyl derivative. Thereby a 25 salt or acid addition product is formed, the N⁴ becoming pentavalent and non-substitutable. Among the strong acids that can be employed in our process are perchloric, chlorosulfonic and sulfuric acids.

30 By the expression "strong acid" as employed in this specification and in the appended claims is to be understood those acids which are capable of forming acid addition products with the p-amino group of sulfanilamide under approximately anhydrous conditions.

In carrying out our invention, sulfanilamide is dissolved or suspended in an appropriate solvent which contains or has added thereto a sufficient amount of a strong mineral or inorganic 40 acid to bind the p-amino group; there is then added a sufficient amount of an acylating agent to react not only with the sulfanilamide but also with any water present in the system, the reaction preferably taking place under as anhydrous conditions as possible. The reaction proceeds quite rapidly when carried out at substantially room temperature. If a minimum of solvent has been used the inorganic acid salt of the N¹-acyl sulfanilamide precipitates out of the reaction 45 mixture. The precipitate is collected by filtration.

tion and is dissolved in water or alkali to remove the combining inorganic acid, whereupon the N^1 -acyl sulfanilamide is precipitated from this solution by adjusting the pH, for example to a value of 4.

By our improved process, the binding of the p-amino group and the acylation at the N^1 -position take place concurrently, that is, in a single step; while the splitting off of the acid group from the N^4 -position is effected by a relatively mild treatment which has practically no effect on the N^1 -acyl group. As a result, much higher yields of the N^1 -acyl derivative are obtained than heretofore and the product can be much more easily separated in pure condition than by the known processes.

Our invention will be described in greater detail in the following examples which are presented for purposes of illustration and not as indicating the limits of the invention.

Example 1

17.2 grams of sulfanilamide are dissolved in 260 cc. of approximately 0.6 molar perchloric acid in acetic acid (prepared by mixing 90 g. of 70-72% perchloric acid with 190 g. acetic anhydride and diluting to 1 liter with glacial acetic acid), and 15 cc. of acetic anhydride are added. The mixture is stirred for one hour, allowing it to come to room temperature, and then filtered with suction. The moist precipitate is dissolved in 20% sodium hydroxide, the solution treated with decolorizing charcoal at room temperature, and filtered. The pH of the filtrate is adjusted to 4 with concentrated hydrochloric acid and stirred for one-half hour at 10° C. The precipitated N^1 -acetyl sulfanilamide is filtered and dried. Yield of crude N^1 -acetyl sulfanilamide is 19.5 grams (92% of theory).

Example 2

17.2 grams of sulfanilamide are dissolved in 275 cc. glacial acetic acid by warming to 56° C. 18 grams of 70-72% perchloric acid are added and then 55 cc. acetic anhydride are run in, keeping the temperature of the mixture below 50° C. The mixture is stirred for one hour. The precipitate is filtered and the wet filter cake dissolved in 15 cc. of water and 75 cc. 25% sodium hydroxide. The solution is treated with decolorizing charcoal, the filtrate adjusted to pH 4 with concentrated hydrochloric acid, and the mixture stirred for one-half hour at 10° C. The precipitate is filtered and dried. Yield of crude N^1 -acetyl sulfanilamide is 17.5 grams (82% of theory).

Example 3

17.2 grams of sulfanilamide are suspended in 92 cc. glacial acetic acid, and 15.1 grams chlorosulfonic acid are added, keeping the temperature below 35° C. 20 cc. acetic anhydride are then added and the mixture stirred for 1½ hours at room temperature. The precipitate is filtered with suction, and the wet filter cake dissolved in 25 cc. water and 75 cc. 25% sodium hydroxide. The pH of the solution is adjusted to 4 with concentrated hydrochloric acid and the mixture stirred for one-half hour at 10° C. The precipitated N^1 -acetyl sulfanilamide is filtered and dried. Yield of crude N^1 -acetyl sulfanilamide is 15.5 grams (72% of theory).

Example 4

17.2 grams of sulfanilamide are suspended in 200 cc. glacial acetic acid and 15 g. of chlor-

sulfonic acid added, keeping the temperature below 35° C. 12 grams of acetyl chloride are added and the mixture stirred for one hour. The product is filtered, dissolved in 20% sodium hydroxide and the pH adjusted to 8. The precipitated material is filtered off and the filtrate adjusted to pH 4, whereupon the N^1 -acetyl sulfanilamide is precipitated. Yield 8.6 grams (about 40% of theory).

10

Example 5

8.6 grams of sulfanilamide are stirred with 50 cc. of a solution of perchloric acid in propionic acid (prepared by mixing 71 g. of 70-72% perchloric acid with 150 g. propionic anhydride) and 12 cc. of propionic anhydride are added. The mixture is stirred for one-half hour, cooled to room temperature and the precipitate filtered. The precipitate is dissolved in water, the solution treated with decolorizing charcoal, and filtered. The filtrate is adjusted to pH 3 and chilled. The precipitated N^1 -propionyl sulfanilamide is collected by filtration and dried. Yield 7.0 g. (62% of theory).

The butyrate, valerate, isovalerate and benzoate can be prepared in the ways above described, and it will be evident that also other acyl derivatives can be manufacture by the use of the corresponding anhydride or halide. In general, no acid should be employed which will oxidize the sulfanilamide under the conditions of the reaction. Sulfuric acid, although it is an oxidizing agent in certain processes, does not act oxidizingly in the process above described.

As will be apparent from the foregoing, the N^4 -salts or addition products of the N^1 -acyl sulfanilamides are difficultly soluble in the solvents that are suitably employed in our process; they accordingly crystallize out during the course of the reaction and so can be efficiently isolated.

We claim:

1. Process for the manufacture of N^1 -acyl sulfanilamides which comprises treating sulfanilamide in an approximately anhydrous solvent with a strong mineral acid of the class consisting of perchloric, chlorosulfonic and sulfuric acids, to form an acid addition product at the p-amino group and subjecting the compound to the action of an acylating agent to form the N^1 -acyl derivative.

2. Process for the manufacture of N^1 -acyl sulfanilamide which comprises treating sulfanilamide in an approximately anhydrous solvent with perchloric acid to form the acid addition product at the p-amino group and subjecting the compound to the action of an acylating agent to form the mono-acyl derivative, the acyl group being at the N^1 -position.

3. Process for the manufacture of N^1 -acyl sulfanilamide which comprises treating sulfanilamide in an approximately anhydrous solvent with chlorosulfonic acid to form the acid addition product at the p-amino group and subjecting the compound to the action of an acylating agent to form the mono-acyl derivative, the acyl group being at the N^1 -position.

4. Process for the manufacture of N^1 -acyl sulfanilamides which comprises forming an acid addition product at the p-amino group of sulfanilamide with a strong inorganic acid in an approximately anhydrous solvent, said acid being a member of the class consisting of perchloric, chlorosulfonic and sulfuric acids, reacting the product with an acylating agent to form the N^1 -

acyl derivative, and thereafter removing the mineral acid from the N^1 -position by treatment with an inorganic base.

5. Process according to claim 1, wherein the acylating agent is an acetylating compound.

6. Process according to claim 1, wherein the acylating agent is a propionylating compound.

7. Process according to claim 1, wherein the reaction is conducted in glacial acetic acid solution at temperatures below 50° C.

8. Process for the manufacture of N^1 -acyl sulfanilamides which comprises treating sulfanilamide in an approximately anhydrous solvent with a strong mineral acid of the class consisting of perchloric, chlorosulfonic and sulfuric acids to bind the p-amino group while simultaneously reacting the compound with an acylating agent to form the N^1 -acyl derivative, dissolv-

ing the reaction product in aqueous sodium hydroxide solution, filtering the solution, adjusting the pH value of the filtrate to about 4, and separating the precipitated N^1 -acyl sulfanilamide.
